UNITED STATES PATENT OFFICE

WILLIAM H. PRIESS, OF UPPER MONTCLAIR, NEW JERSEY, ASSIGNEE, BY MESNE ASSIGNMENTS, TO GENERAL ELECTRIC COMPANY, A CORPORATION OF NEW YORK

ELECTRICAL CONDENSER

Original application filed January 6, 1922, Serial No. 527,449. Divided and this application filed September 18, 1926. Serial No. 136,210.

This application is a division of my application Serial No. 527,449, filed January 6, 1922.

This invention relates to electrical condensers.

The condensers of the present invention, of which several forms are illustrated and described, are of general application or use. By way of example, they are adapted for use as series antenna condensers, grid condensers, key condensers, bypass condensers, dummy circuit condensers and receiving circuit condensers, for amateur or commercial use in radio communication.

The condenser of this invention comprises a stack composed of alternate sheets of conductors and dielectric, the conductors comprising foil preferably of lead, tin or copper, and the dielectric being preferably of mica, with the sheets of foil and dielectric in intimate contact, or substantially so, and preferably treated with wax or some other insulating material.

An object of the invention is to provide a low cost, compact condenser of high efficiency.

Another object of the invention is to provide an improved clamp for the stack.

Another object of the invention is to provide clamping means which exerts a spring pressure on the stack to maintain the elements or sheets thereof in intimate contact.

Another object of the invention is to provide improved means for securing and protecting the terminal leads.

Another object of the invention is to provide a construction of series section stack in which the leads may be brought out at opposite ends, irrespective of the number of sections.

Another object of the invention is to provide an improved casing for the condenser stack.

Of the drawings,

Fig. 1 is an elevation of an embodiment in an assembled condenser;

Fig. 2 is a bottom plan view thereof;

Fig. 3 is an end view looking in the direction of the arrow, Fig. 2;

Fig. 4 is a sectional plan view of one end

of the condenser, on line 4—4 of Fig. 1, illustrating the manner of attaching the leads and embedding the same;

Fig. 5 is a perspective view of one of the casing or clamping parts;

Fig. 6 is a perspective view of another casing or clamping part, the broken lines at the left indicating the unstressed condition of the part prior to assembly;

Figs. 7 and 8 are perspective views of insulating parts.

Fig. 9 is a detail of a vertical section taken at right angles to the showing in Fig. 4.

In the form of my invention illustrated, the casing or clamp comprises, as shown in Fig. 5, a box-like part, clip or member comprising a bottom or transverse portion 16 and side portions 18 extending vertically therefrom, the remaining opposite free edges of the surface 16 being provided with outwardly upturned ribs or edges 17 constituting reinforcing or stiffening means with the side portions 18.

At the edges of the side portions 18 are lugs or tongues 19 for the purpose hereinafter described. This box-like member is provided with inwardly-projecting lips 20 at opposite ends, which are sufficiently separated to provide a casing open at its opposite ends 21.

The member of Fig. 5 consists preferably of sheet metal such as iron, and is of a form which may be very easily stamped out and shaped as illustrated in Fig. 5.

In assembling the condenser stack within this part, the stack is preferably insulated therefrom by means of an insulating sheet 22, (Figs. 1 and 3) preferably of fish paper, separately illustrated in Fig. 8, which has reduced portions 23 at opposite ends providing notches 24 at the several corners thereof.

The sheet 22 is assembled against the inner surface of the bottom 16 of the part 15 with its ends 23 projecting through the open ends 21 of 15, as illustrated in Figs. 1 and 2,

and with its notches 24 co-operating with the inwardly-directed lips 20 of the member of Fig. 5, whereby the insulating plate 22 is locked within said member.

The two insulating parts 25, illustrated in Fig. 7, which may consist likewise of some cheap insulating material such as fish paper, are next as-

sembled vertically against the inner walls 18 of the member of Fig. 5. Each of the two insulating strips 25 has at its opposite ends offset portions 26 providing intermediate portions 27 at right angles to the general plane of the part 25. The portions of the parts 25 between 27-27 engage the inner sides of the casing portions 18, (Fig. 5), the bends 27 engage the lips 20 of the casing member of Fig. 5, and the ends 26 project beyond the casing proper as illustrated in Figs. 1 and 2. The parts 27, co-operating with the lips 20, lock the insulating members 25 within the casing against endwise movement. After these insulating parts 22 and 25 are assembled within the casing, the stack is then positioned against them. Upon the stack is placed a second fish paper sheet or plate 28 (Figs. 1 and 3) identical in contour with member 22 illustrated in Fig. 8. This insulating plate 28 like 22 is held from condenser movement by the inwardly-projecting lips 20 engaging in notches 24, Fig. 8. After plates 22, 28, 25, 25 have been positioned, a spring plate 29, preferably of spring steel such as vanadium steel, separately shown in Fig. 6, is then secured in position on top of the member of Fig. 5 as illustrated in Figs. 1 and 3, this plate 29 lying face to face with insulating plate 28. This securing is done preferably by passing the tongues 19 at one side of the member of Fig. 5 through slots or holes 30 along one edge of the member 29 (or vice versa construction) and then bending the tongues 19 over to lock one side of the plate 29 in position as illustrated in Figs. 1 and 3, and after this is done the opposite side of spring member 29 is pressed down flat, putting it under tension and then is secured in such condition by inserting the opposite pair of tongues 19 of the member of Fig. 5 through the opposite pair of slots 30 in member 29 and bending them over, securing plate 29 in clamping relation to the condenser stack. Inasmuch as the total thicknesses of the stack and fish paper insulators 22 and 28 exceed the height of the side portions 18 of the member of Fig. 5, the member 29 when locked in position exerts a pressure upon the active area of the stack, and if member 29 is a spring the stack is kept under constant pressure irrespective of temperature changes therein causing expansion and contraction thereof and thus making the losses lower, reducing brushing, and maintaining the capacity constant. The plate 29 is placed parallel with the sheets composing the stack and the complete clamp or casing comprising the combined parts of Figs. 5 and 6 constitutes a rigid connection between the flat portions engaging opposite sides of the stack, the parts 18 providing a rigid connection at right angles to said flat parts. The angular portion 31 extending from the plate 29 is for the pur-

pose of securing the condenser to any suitable support.

The portions of the insulators 22, 25 and 28 projecting beyond opposite ends of the casing or clamp of Fig. 5 provide open-ended box-like insulating structures 32 (Figs. 4 and 9) at opposite ends of the casing beyond the stack through which pass or project the stranded leads 9a, 10a, 11a and 12. As shown more clearly in Figs. 1, 2, 3, 4 and 9, these leads are arranged or connected to the several parts of the condenser stack in spaced-apart and staggered relation, whereby they are more thoroughly insulated from each other. Furthermore, as shown in Figs. 3 and 9, these leads project from the stack at such points that they are separated from each other by the fish paper or mica separators 13. The leads are also protected from contact with the metal casing by the box-like open-ended projecting portions 32 of insulating material. The box-like portions 32, after the condenser is assembled, are filled with some fusible insulating material such as a mixture of hot molten beeswax and rosin or with molten sulfur which is solid at normal temperatures. This forms upon solidification an embedment for the several leads 9a, 10a, 11a and 12, which grips them and maintains them rigidly in position and prevents their bending around their points of connection to the foil terminals. The leads therefore are very rigidly and securely positioned on the condenser, first soldering their fanned-out ends indicated generally at 33, 34 and 35 to the foil terminals in the manner described above, and secondly by embedding the inner portions thereof in said solid, insulating material which prevents all movement thereof adjacent the inner ends of the leads, the outer ends of the leads, of course, being free to be bent for attachment to different points.

In the form of the condenser herein illustrated as a specific embodiment of the invention, that is, a series antenna condenser, the condenser may be connected in the radio circuit to give different capacities. For this purpose, the lead 9a is the common lead of the system, while the leads 10a, 11a and 12 may be each connected up as desired to form a condenser circuit with the lead 9a. In the specific embodiment of the invention here illustrated, with the leads 9a and 10a connected, there is a capacity of .0004 mfd.; with the leads 9a and 11a connected, there is a capacity of .0002 mfd.; and with the leads 9a and 12 connected, there is a capacity of .0003 mfd.

The condenser stack is thoroughly insulated from the casing by said insulating plates 22, 25, and 28 arranged to form terminal insulators 32, filled with suitable insulating material such as those specified above.

By providing some conductive foils 36, 37, and 38, of greater thickness and increased

tensile strength over the other foils, the foil terminals at opposite ends of the condenser are strengthened in such a manner that the fanned-out ends of the terminal leads, previously described, may be securely soldered thereto, without danger of tearing the reinforced foil tabs. The foils 36, 37 and 38, of increased thickness and tensile strength, are preferably positioned on top of the several sections and immediately subjacent to the section separators 13 and insulating plate 28, being extended beyond the stack proper into space 32 for a sufficient distance to permit the foil tabs 39, 40, 41, of the condenser stack sections to be soldered thereto and themselves be soldered to the fanned out ends of the terminal leads. Furthermore, in this construction there is very little danger of tearing the leads off for the reasons above mentioned. The plate 29 is of spring steel, and all the parts are easily formed and easily assembled, reducing the cost of the condenser to a minimum.

The embodiments or fillers within the box-like portions 32 (Fig. 4) provide a thorough insulation and coating of the terminal leads, locking them in position, preventing a side motion which might in time break them.

I particularly point out and distinctly claim the part, improvement, or combination which I claim as my invention or discovery as follows:

1. An electrical condenser comprising armature sheets arranged in a stack with an interposed dielectric sheet; a box-like casing of insulating material open at opposite ends and otherwise enclosing the condenser sheets; and a box-like metal casing partially enclosing and rigidly supporting said insulating casing and open at opposite ends registering with the open ends of the insulating casing, the open ends of the insulating casing extending beyond the open ends of the metal casing; the metallic casing holding the insulating casing in clamping relation with the stack of condenser sheets; and the condenser terminals extending out thru said open ends of the insulating and metal casings.

2. An electrical condenser comprising armature sheets and an interposed dielectric sheet; a box-like casing of insulating material open at opposite ends and otherwise enclosing the condenser sheets; and a box-like casing of metal open at opposite ends registering with the open ends of the insulating casing and having portions interlocking with portions of the insulating casing and otherwise enclosing the insulating casing.

3. An electrical condenser comprising armature sheets and an interposed dielectric sheet, and a metal casing in two parts respectively having surfaces face to face with said sheets, said casing laterally enclosing the condenser armature sheets, and a casing consisting of strips of insulating material inter-

posed between the condenser sheets and the metallic casing; one of said metallic casing parts being slotted and the other having tongues extending thru the slots and bent to resiliently lock the parts together around the insulating casing in condition pressing the latter against the condenser sheets.

4. An electrical condenser comprising armature sheets and an interposed dielectric sheet; and a metal casing in two parts enclosing condenser armature sheets, and an insulating casing interposed between the condenser sheets and metallic casing; one of said metallic casing parts being slotted and the other having tongues extending thru the slots and bent to lock the casing parts together in compressing relation to the insulating casing and condenser sheets.

5. An electrical condenser comprising armature sheets and an interposed dielectric sheet; a metal casing in two parts respectively having surfaces face to face with said sheets, said casing enclosing the condenser armature sheets, and one of said metal casing parts facing the sheets being resilient; one of said casing parts being slotted and the other having tongues extending thru the slots and bent to lock the casing parts together; and a casing of insulating material interposed between the condenser sheets and the metallic casing and held by the latter in resilient compressing relation to the condenser sheets.

6. An electrical condenser comprising armature sheets and an interposed dielectric sheet; and a box-like metal casing therefor having inwardly extending lips; and insulating sheets between the condenser sheets and the casing and locked in the latter by said casing lips.

7. An electrical condenser comprising armature sheets and an interposed dielectric sheet; a box-like metal casing therefor having inwardly extending lips; and means enclosing the condenser sheets and insulating them from the metal casing, locked in the latter by said lips, and comprising two insulating sheets having portions of less width projecting from opposite ends of the metal casing, the casing lips lying in the shoulders between the greater and lesser widths of the insulating sheets, and two insulating sheets interposed between the first two insulating sheets at angles thereto and having offset portions projecting from opposite ends of the metal casing, said offset portions extending inwardly of the casing and the casing lips lying in the shoulders of the offset portions.

8. An electrical condenser comprising armature sheets and an interposed dielectric sheet; a box-like metal casing in two parts and having opposite open ends but otherwise enclosing the condenser sheets; and insulating sheets between the condenser armatures and the metal casing; one of the metal casing parts having inwardly extending lips hold-

ing said insulating sheets in place within the open-ended metal casing; and the two metal casing parts being formed respectively with slots and with tongues extending thru the slots and bent to lock the metal casing around the insulating sheets and condenser armatures.

9. An electrical condenser including armature sheets and an interposed dielectric sheet; a box-like structure of insulating material extending around the condenser sheets and having open ends projecting beyond said sheets; a box-like structure of sheet metal extending around said insulating structure but the ends of the latter projecting beyond said sheet metal structure; condenser terminals extending from the condenser armatures out thru said open ends of the insulating structure; and embedments of insulating material cast in the spaces surrounding said terminals between the condenser armature sheets and the open ends of the insulating structure.

10. An electrical condenser comprising armature sheets and an interposed dielectric sheet; a rigid metal casing therefor having opposite open ends; certain of the armature sheets having greater tensile strength than others; at least three condenser terminals at one end of the casing, each including at least one of such stronger sheets; and a corresponding number of terminal leads fused to said terminals, insulated from said metal casing, and located in spaced apart and staggered relation to one another at one end of the casing.

11. A sheet-stack condenser including metal foil armature sheets and an interposed dielectric sheet arranged in a stack; a conductive sheet having thickness and tensile strength greater than said foil sheets and arranged face to face with said stack; a casing extending around the stack and including sheet insulating material having a face lying against said conductive sheet; said sheet insulating material, foils and conductive sheet extending beyond an end of the stack and the projecting foils being made conductively integral with said conductive sheet adjacent said sheet insulating material forming a strong terminal for the condenser beyond the stack but within the sheet insulating material; and metallic means holding in close face to face relation, the sheet insulating material, the conductive sheet and the stack of condenser foils and interposed dielectric sheet.

12. In an electrical condenser, a stack comprising alternate sheets of foil and dielectric, a metal clamp surrounding said stack and open at its opposite ends, and insulating sheets surrounding said stack and insulating the stack from the clamp, said clamp and insulating sheets being provided with co-operating means for locking the latter within the clamp.

13. In an electrical condenser, a stack comprising alternate sheets of foil and dielectric and having foil terminals, a two-part metal clamp surrounding said stack and including a spring member, the two parts being secured together around the stack to exert a spring pressure thereon and open at its opposite ends, sheets of insulation interposed between said stack and clamp, projecting beyond the opposite open ends of said clamp and providing box-like structures of insulating material at opposite ends, means being provided on the clamp for securing the stack and insulating sheets therein, flexible leads soldered to the foil terminals of said condenser and extending through said box-like structures, and an embedment of fusible solid insulating material within said box-like structures, sealing in said leads and preventing movement thereof.

14. A sheet-stack condenser including flexible armature sheets and an interposed dielectric sheet arranged in a stack; a sheet insulating casing extending around the stack, projecting beyond an end thereof and itself formed with an open end, and establishing an open ended space at said stack end, the ends of said flexible armature sheets extending into said end space; and a sheet metal casing extending around the stack holding the faces of the insulating casing in contact with the faces of the stack, and extending around the portion of the insulating casing which extends beyond the stack and reenforcing said portion and likewise having an open end; a lead extending from outside into said end space; said projecting ends of the flexible armature in said end space being made conductively integral with one another and with the end of said lead within said end space; and readily flexible insulating material supported in said end space by said projecting portion of the insulating casing, said insulating material embedding and supporting said foils and the lead united therewith in said end space.

15. In an electrical condenser, a stack comprising sections connected in series, separators between sections, leads extending from certain of said sections, whereby a combination of capacities may be obtained, a casing enclosing said stack and having open-ended portions projecting beyond the stack through which said leads extend, said leads being staggered and spaced from each other and separated by said sectional separators, and a solid embedment of insulating material surrounding said leads within said open-ended portions of the condenser casing.

16. In an electrical condenser, a stack comprising alternate sheets of foil and dielectric, two strips of insulating material arranged face to face with opposite faces of said stack; and clamping means comprising metal plates engaging the outer faces of said insulating

strips and having rigid lateral portions relatively bent over each other holding the insulating strips in clamping relation with the faces of the stack, at least one of said metal plates being springy to maintain said clamping pressure resiliently.

17. In an electrical condenser, a stack comprising alternate sheets of foil and dielectric, sheet metal clamping means therefor, sheets of insulating material interposed between said clamping means and the stack and projecting beyond an end of the stack, said clamping means extending laterally around the stack and insulating sheets and having adjacent edges formed integral with relatively movable interlocking means holding the clamp in operative relation; a lead connected to said end of the stack and extending between said insulating sheets; and a solid readily fusible insulating material supported by said projecting portions of the insulating sheets, said fusible material in solidified condition supporting said extending portion of said lead.

18. In an electrical condenser, a stack having a metal clamp therearound, insulating sheets interposed between said clamp and opposite sides of said stack and projecting beyond the stack at opposite ends, insulating end pieces retained in position by said insulating sheets, and leads connected to opposite ends of the stack and extending through said insulating end pieces between said insulating sheets.

19. In an electrical condenser, a stack having leads connected thereto at opposite ends, a metal casing enclosing said stack and having insulating walls at opposite ends and insulating bushings on said walls through which said leads and said insulation extend.

20. In an electrical condenser, a stack, a metal casing extending around the stack but open at its ends; insulating means between the faces of the stack and the inner faces of said metal casing; hollow insulating means extending thru the open ends of said metal casing and projecting beyond the casing ends; leads connected to the opposite ends of said stack and extending through said hollow projecting insulating means; and a filler of solid readily fusible insulating material in said hollow projecting insulating means and supporting said leads extending therethrough.

21. A sheet-stack condenser including armature sheets and a dielectric sheet stacked together face to face, and a sheet-metal clamping casing therefor including a member formed with a flat portion engaging one face of the stack, two opposite integral sides lying opposite the edges of the stack, and two integral stiffeners for the sheet metal member consisting of its integral end edges extending outwardly from said flat portion.

22. A sheet-metal condenser including armature sheets and an interposed dielectric

sheet stacked together face to face; a casing therefor including a sheet metal member formed with a flat portion lying face to face with the stack and formed also with two integral side portions themselves formed with integral inwardly projecting lips; an insulating strip interposed between one of said integral side portions and the stack; and an insulating strip interposed between said flat portion and a face of the stack; said two insulating strips being held by said lips from endwise movement.

23. A sheet stack condenser including armature sheets and an interposed dielectric sheet stacked together face to face; a casing therefor including a sheet-metal member formed with a flat portion lying face to face with the stack and formed also with two integral side portions themselves formed with integral inwardly projecting lips; and an insulating strip interposed between said flat portion and a face of the stack and held by said lips from endwise movement.

24. A sheet-stack condenser including armature sheets and an interposed dielectric sheet stacked together face to face; a casing therefor including a sheet metal member formed with a flat portion lying face to face with the stack and formed also with two integral side portions themselves formed with integral inwardly projecting lips; and an insulating strip interposed between one of said integral side portions and the stack and held by said lips from endwise movement.

25. A sheet-stack condenser including armature sheets and an interposed dielectric sheet stacked together face to face; a casing therefor including a sheet metal member formed with a flat portion lying face to face with the stack; and sheet insulating material between the stack and said metal member; the metal member being formed at its portions lying beyond the ends of the stack with integral inwardly extending portions lying in the path of endwise movement of said sheet insulating material and preventing such movement.

26. A sheet-stack condenser including armature sheets and an interposed dielectric sheet stacked together face to face, a thin-walled insulating casing extending around the stack; and a sheet metal casing extending around said insulating casing and formed with integral portions extending inwardly at opposite ends of the stack and holding the insulating casing from relative endwise movements.

27. A sheet-stack condenser including armature sheets and an interposed dielectric sheet stacked together face to face; an insulating casing extending around the faces and sides of the stack; and a sheet metal casing extending around said insulating casing and formed with integral portions projecting inwardly at opposite ends of the stack hold-

ing the insulating casing from relative endwise movements; said insulating casing being formed with a narrower end portion projecting endwise beyond said inwardly projecting metallic casing portions.

28. In an electrical condenser, the combination with armature sheets and an interposed dielectric sheet, of a box-like insulating casing extending around the condenser sheets and including four insulating strips at right angles to one another; and a sheet metal casing extending around said insulating casing and including two portions clamping two opposite units of said insulating strips against the condenser sheets, said metallic casing including also inwardly projecting portions holding the other two insulating strips which are not clamped against the condenser sheets, from relative endwise movements.

29. A sheet metal condenser including armature sheets and an interposed dielectric sheet, the edges of the sheets lying at the sides of the stack; a sheet metal casing extending around the stack and spaced from the sides thereof; and sheet insulating means between the faces of the stack and the sheet metal casing; said casing having adjacent portions extending longitudinally of the stack and formed with integral interlocking means holding the casing in clamping relation with said sheet insulating means and the faces of the stack thereby retaining the condenser armature and dielectric sheets in operative relation with one another.

30. A sheet-stack condenser including armature sheets and an interposed dielectric sheet, the edges of the sheets lying at the sides of the stack; a metallic casing extending around the faces and sides of the stack; means insulating the inner faces of the casing from the faces of the stack, the faces of the casing holding said insulating means against the faces of the stack; the casing having a construction forming spaces between its sides and the sides of the stack; and a readily fusible insulating embedment filling said spaces and embedding the edges of the stack-sheets, said fillers each extending between the two faces of the metallic casing which hold said insulating means against the stack-faces.

31. An electrical condenser including armature sheets stacked together with an interposed dielectric sheet; a casing of insulating material extending around said condenser sheets and having two portions arranged face to face with said sheets; and a casing of sheet metal extending around the insulating casing holding the latter in place and compressing its said face to face portions against the stack of sheets holding the sheets in operative surface relation to one another in the stack.

32. An electrical condenser including ar-

mature sheets stacked together with an interposed dielectric sheet; strips of insulating material facing the surfaces of said stack; and a sheet metal stack-clamping casing having surfaces face to face with the stack faces, 70 engaging the insulating strips and having adjacent edges formed with integral cooperating means movable relative to one another tightening the casing-faces as a clamp toward the faces of the stack and holding the 75 condenser sheets in operative surface relation to one another in the stack.

33. A sheet-stack condenser including armature sheets and an interposed dielectric sheet stacked together face to face; and a sheet metal stack-clamping casing extending laterally around the stack and having surfaces facing the stack faces and having adjacent edges formed integrally with relatively movable interlocking means holding the 85 surfaces of the casing facing the stack-surfaces in positions clamping the condenser sheets together in the stack.

In testimony whereof I hereunto affix my signature.

WILLIAM H. PRIESS.
